UNITED STATES PATENT OFFICE.

MARIO SCHIESARI, OF NEW YORK, N. Y.

VARIABLE PROPELLER.

Application filed July 11, 1922. Serial No. 574,222.

To all whom it may concern:

Be it known that I, MARIO SCHIESARI, a citizen of the United States, residing at New York, in the county and State of New York, have invented certain new and useful Improvements in Variable Propellers, of which the following is a full, clear, and exact description, reference being had to the accompanying drawings, forming a part of this specification.

This invention relates to extensible propellers consisting of a plurality of inclined planes or blades connected to an axle and to each other by flexible retaining means, and rendered operative through the utilization of centrifugal force, of the type described by me in a co-pending application filed July 14, 1921, having for title "Method and apparatus for aerial propulsion," Serial No. 484,825; and its main object is to provide a special construction of propeller, whereby variable area in the sweep of the propeller elements may be automatically obtained.

A further object is to provide a novel and improved construction of propeller whereby variable area in the sweep of the propeller elements may be automatically obtained, and at the same time the pitch of the same automatically changed.

A still further object is to provide a propeller the diameter and pitch of which may be controlled automatically or manually, at the will of the operator.

With these and other objects in view, as will more fully appear as the description proceeds, my invention furthermore consists in certain novel constructions and arrangements of parts as will be hereafter fully described and claimed in the appended claims.

In my other patent application above referred to, I describe a propeller of a novel and improved design, the action of which is based on utilizing the lifting or propelling force obtained through causing inclined planes or blades connected to an axle and to each other by flexible retaining means, to travel in a circular path at a suitable speed; said propeller having a variable radius of action, under the control of the operator. The advantages of this type of propeller

have been fully set forth in said patent application; the same being substantially an adaptation of aerofoil elements in combination with a rotating axle, the lifting or propelling power developed by said aerofoils set at a certain angle of incidence to their plane of travel being made available through a novel method of exploitation of centrifugal force. In order to attain greater efficiency in a propeller, it is as a rule desirable to make the same of a large diameter, with a low angle of incidence; but there are instances where the best efficiency is obtained with a large diameter and a high angle of incidence, and it may broadly be stated, that while it is desirable to have both these factors variable, no general rule may be set down as to how the variations should take place, since the same should be different in order to meet different conditions of power, speed, resistance and density of the medium in which the propeller revolves, etc. With propellers of ordinary design however, there are sharp limitations imposed by practice in determining these factors of construction.

In another co-pending patent application filed by me March 13, 1922, having for title "Extensible propeller," Serial No. 543,303, I have described an improved propeller of the same type, but provided with means whereby variations in the diameter of the same will cause simultaneous variations in the angle of incidence of its elements; and in the same I have referred to the advantages to be derived from a construction where the angle of incidence decreases with the increasing of the diameter, this tending to equalize the torque on the axle, and therefore to realize conditions where the speed of the engine may be maintained substantially constant. This is true where the density of the medium in which the propeller revolves is practically constant.

With increasing altitude, however, both the atmospheric pressure and density decrease, and since it is now possible to insure the efficiency of the engine under these conditions by equipping the same with a supercharger, in order to enable the propeller to balance the generation of motive power it will be necessary not only to in-

crease its diameter, but also to increase the angle of incidence of its elements.

The construction described in my second patent application above referred to, is however equally applicable to cases where it is desired to have the pitch decrease with the increasing of the diameter, and cases where the pitch is made to increase with the diameter; the result being dependent merely on the proper design of the elements of construction shown. It is at any rate evident that the variations of these two factors may be caused to take place in such a manner that even with a decreasing pitch an increase in diameter will mean an increase in the power consumed by the propeller at the same speed, and vice versa; so that an increase in diameter will tend to counterbalance the increase in the number of revolutions which would take place with the increase of the rarefaction of the air.

With manually operated propellers having variable pitch and variable diameter, however, the operation of the same is entirely dependent upon the pilot, who has, as a rule, enough to occupy his attention during flight. There are circumstances furthermore, that the pilot cannot foresee, where it would be desirable that suitable changes altering the power absorbed by the propeller should take place automatically; for instances when air pockets are encountered, or when the engine misses fire or for any other reason it loses power and slows down. On the other hand there are conditions of flight where the variations of these factors should be under the control of the pilot; for instance in climbing, when the pilot should be able to choose and set permanently the best diameter, to which corresponds the best climbing angle.

In order to render automatic the functioning of the propeller, I make use of the antagonistic actions of a spring or other elastic medium tending to contract and centrifugal force tending to expand the same; so that the diameter will increase or decrease when similar variations in the motor speed take place. Thus, if the density of the air decreases, the diameter of the propeller will increase with a consequent increase in the load; and if the engine slows down the diameter will decrease, and the propeller will not overload the engine, but will assume the dimensions of an airscrew adapted for the horse-power that the motor is actually delivering at the time. If the pitch of the propeller is not variable the load variations will depend only on the variations of the diameter, while if also the pitch is variable, said load variations will be increased or decreased according to the variations of said pitch.

In the drawings I show different constructions of propellers built according to

my invention, having both a variable diameter and a variable pitch; it being understood however, that said drawings are intended as illustrative of my invention, but not in a limiting sense.

Referring to said drawings:

Fig. 1 is a view in perspective of an aeroplane fitted with my improved propeller;

Figs. 2 and 3 are diagrammatic views of the composition of centrifugal and lifting forces taking place in the operation of my propeller;

Fig. 4 is a plan view partly sectioned and broken away, showing the construction of my propeller;

Fig. 5 is a cross sectional view in elevation of one of the aerofoils used in connection with a propeller having a variable pitch; and,

Figs. 6, 7, 8, 9, are detail cross sectional views of hubs of propellers showing different constructions of the same.

One of the advantages, which may be derived from a design of propeller such as shown, and which is quite important, is the possibility of having the pitch decrease as the diameter decreases, until it actually assumes a negative angle; by setting the propeller at such an angle, and by giving full speed, a strong braking effect will be obtained, which will enable the pilot to land in a small landing ground.

In the drawings, Figs. 1, 4 and 5, a propeller possessed of such an advantage is shown, where a decrease in the diameter will effect a decrease in the pitch, and finally its reversal.

The general appearance of my propeller is shown in Fig. 1, where:

10 represents: revolving aerofoil elements in a get-away position; small diameter and minimum positive pitch.

11 represents: flying position of propeller; maximum diameter and maximum positive pitch.

12 represents: reversed propeller; negative pitch.

13 represents: flexible cable connecting the aerofoil elements to each other and to the revolving shaft.

In Figs. 2 and 3, in order to facilitate a thorough understanding of the present invention, I show in a diagrammatic form the composition of forces governing the operation of my improved propeller. In the same, for the sake of clarity, the inclination of line BP has been greatly exaggerated, and the drag coefficient, being small enough to be negligible, is omitted. In the same:

B designates the point of attachment;

P designates the point of application of forces;

C designates the centrifugal force in P;

f designates the lift-drag exerted in P.

Resultant R will be in alignment with BP;

the moment of said resultant about the fixed point B will be zero; and the system will consequently be in equilibrium.

By taking movements of the component forces about B we find:

$$cm = fn \quad (1)$$

$$\frac{c}{f} = \frac{n}{m} \quad (2)$$

10 equation (2) giving the complete solution of the dynamic problem.

From it, if two elements of the system are assumed, all the other elements will immediately be found. In practice, the magnitude 15 of the centrifugal force will be greater than the magnitude of the lifting force, therefore the flexible member BP will be only slightly inclined upwardly in respect to the horizontal.

20 In Fig. 3, I show how two lifting (aerofoils) forces acting simultaneously will compound themselves in a double lifting force axially directed.

In Figs. 4, 7, I show the general construction of my propeller, in which six sections of 25 a single cable 14 are wound together on a core 15, secured by key 16 to shaft 17.

Core 15 is encased in drum 18, loosely mounted on shaft 17, forming a reel for cable 14; said drum being however connected to said shaft 17 by two spiral springs 19, 20, wound in the direction opposite to that of the cable and attached at their inner end as at 21, respectively to shaft 17 and to a collar 22 rendered integral therewith by a key 23, and at their outer ends to the drum itself, as at 23. The shaft is supposed to rotate in the direction of the cable windings, as the arrow indicates, pulling along drum 18

30 through the elastic connection provided by springs 19, 20; and it is to be noted that a movement of rotation of the drum relative to the shaft in the opposite direction, would tend to compress the springs. The drum is provided with six idler rollers 24 around which each cable section is bent to extend from the drum outwardly to and around a sheave 27 or 28 of a frame 29, emerging therefrom in the direction of the next sheave 28' or 27" of the next frame, and after encircling said sheave returning to the drum, to complete one of the three loops by means of which cable 14 connects to each other all the frames carrying the aerofoil elements.

45 By rotating shaft 17, and with it drum 18, the sections of cable 14 are carried around, and with it the three aerofoil frames carried thereby; centrifugal force tending to extend the sections of cable 14 away from drum 18, and being opposed by the tension of springs 19, 20.

50 When the cable 14 is entirely wound on core 15, the frames carrying the aerofoil elements are held firmly in the position shown 60 in dotted lines in Fig. 4, by having head 30

of each frame inserted between the flanges of drum 18. This retracted position is maintained as long as the tension of springs 19, 20, is greater than the pull exerted by centrifugal force on cable 14. If at any moment the pull of the centrifugal force should be greater than the tension of said springs, the resistance of cable 14 on rollers 24 will cause the rotation of drum 18 to slow down, winding up more and more springs 19, 20, 75 but allowing cable 14 to extend up to a point where the increasing tension of springs 19, 20 will again balance the pull exerted on cable 14 by the centrifugal force.

Each frame 29 carrying, as stated, an aerofoil element, a flexible expandable propeller will thus have been obtained, the diameter of which will increase or decrease, when the centrifugal force increases or decreases; and this in practice will mean that where the air 80 resistance decreases and the engine tends therefore to increase its number of revolutions, an excessive increase will be checked by the propeller increasing its diameter automatically. It also will mean that, 85 should the engine for any reason lessen the power delivered, and slow down, the propeller would not overload the motor, because the centrifugal force would decrease so that springs 19, 20, would be enabled to rewind 90 cable 14, diminishing the propeller's diameter up to the point where the two opposing forces would again balance each other.

When a variable pitch is desired in the propeller besides a variable diameter, a construction may be resorted to such as described in my co-pending patent application above-mentioned for improvements in "extensible propellers," Serial No. 543,303, and is shown in Figs. 4, 5.

95 In the same it is seen that each aerofoil element 30 is pivoted at 31, 32, to frame 29, and is held at a certain angle of incidence by positioning screws 33, 34, inserted into the threaded hub of sheaves 27, 28. Screws 100 33, 34, are only capable of axial travel, their rotation being prevented by a pin 37, inserted in longitudinal groove 38.

105 Feeding a given length of cable to increase the diameter of the propeller, will 110 cause sheaves 27, 28, to revolve, and therefore screws 33, 34, will axially travel in opposite directions; thus proportionately varying the angle of incidence of the aerofoil element.

115 The variations of said angle of incidence of the aerofoils in relation to the diameter of the propeller depending not only from the length of cable which has been fed or retracted, but also on the diameter of sheave 27, 28, and on the pitch 120 of screws 33, 34, the same may be regulated at will, to suit all requirements which may arise in different cases.

125 As stated before, in certain cases, for 130

instance during climb, or in landing, etc., it might be necessary or convenient to set a certain diameter for the propeller, independently from the action which might be exerted by centrifugal force at full engine speed. To this end the pilot by means of suitable levers not shown in the drawings, may control a device consisting of a clutch collar 39 slidably keyed on collar 22, and provided with pins 40 adapted to enter perforations 41 through flange 42 of collar 22, and through one of the flanges of drum 18. When the pilot, operating the lever (not shown), moves pins 40 towards drum 18, said pins engaging perforations 41 will connect shaft 17, and therefore core 15 to said drum. All reciprocal variations of speed between the two parts becoming thus prevented, the propeller's diameter 20 will be maintained constant.

In landing, when cable 14 is nearly all retracted, and the aerofoil elements assume a zero angle of incidence, heads 30 of frames 29 are nearing their housings between the 25 flanges of the drum. As soon as cable 14 is retracted a little further, the aerofoil elements will assume a small negative angle which may manually be made permanent at the will of the pilot, by causing pins 30 40 to engage perforations 41, as soon as said heads have entered their housings in their resting position.

At this moment the pilot, by giving again full speed to the motor, will obtain a strong 35 braking effect, antagonistic to the travel of the machine.

In starting, the pilot, through the manual control will have to let out cable 14 for a short distance, and then fix it in the 40 new extended position, before giving full speed to the motor.

Instead of the springs shown, it is obvious that springs of other types may be used, or other elastic mediums, such as, 45 for instance, compressed air, as shown in Fig. 6. In the same, 43 designates a chamber containing air under high pressure, pumped through valve 44, and 45 a piston made air tight by piston rings 46, playing 50 into said chamber.

Said piston is screwed on threaded part 47 of shaft 48, and is compelled to rotate at the same speed as chamber 43, being 55 connected to the same by means of pins 49 inserted in longitudinal grooves 50.

Said chamber 43 is integral with reel 51, and should the same revolve at a lower speed than shaft 48, as must be the case if the propeller's diameter is increasing, 60 piston 45 would be caused to unscrew from part 47, and to travel towards the bottom of chamber 43 up to a point where the increased pressure of the air would again balance the stronger tension on the cable

sections, exerted by centrifugal force. 65 Should the centrifugal force decrease, the excess of pressure in chamber 43 would force back piston 45, causing the same to screw itself again upon part 47 by rotating in the opposite direction, causing winding 70 up of the cable, and decrease of the propeller's diameter.

The thread of part 47 will therefore be designed so that the motion of piston 45 will compress the enclosed air so as to 75 maintain practically constant the relations between said pressure, the centrifugal force, and the diameter of the propeller. A spring or springs may be added, if desired, to co-operate with the reaction of said air under 80 pressure, and many other different arrangements may be devised, without departing from the spirit of my invention.

In Fig. 8 I show another construction 85 whereby my invention may be carried into practice. In the same, 52, 53, designate two flanges, integral with shaft 54, within which is retained, so as to be free to revolve, drum 55. Said drum is hollow, and is attached to shaft 54 by means of three 90 spiral springs 56, acting in a way similar to that described in connection with springs 19, 20, of the device shown in Fig. 7.

Drum 55 is formed on the outside, with a helical groove 57, adapted to receive the 95 six sections of cable 58, which will thus become wound on the drum along a cylindrical spiral, instead of a flat spiral. This arrangement permits of decreasing the diameter of the drum, while its thickness will 100 be increased. The cable sections are guided, during their extension and retraction, by idler roller 59, which are mounted on threaded pins 60, and will therefore follow the longitudinal or axial travel of the cable 105 sections.

In connection with this arrangement, a different device for substituting manual control to automatic, is shown. The same consists of a plurality of radial arms 61, having their outer end pivoted at 62 to flange 53, and their free inner end abutting against a flange 64 of a collar 65 slidably mounted on the hub of said flanges 53, so as to be capable of axial motion under the control 115 of the operator.

Arms 61 are formed with a projection 66, inserted through openings 67 in flange 53, which will, when collar 65 is forced outwardly, exert a braking action against drum 120 55, and thus render the same integral with shaft 54.

The advantage of such an arrangement is that connection between the reel on which the cable sections are wound, and the shaft, 125 may be formed at any relative position of said two members. In Fig. 9 I show a similar arrangement, where instead of the

springs, a compressed air chamber is used, operating in the manner explained in connection with Fig. 6.

In order to maintain the rigidity of the system, and to prevent possible displacements of the wings in relation to the cable section to which they are attached, it will be preferable to provide armatures 29 with tubular guide pieces 68, 69, through which

10 run the circumferential cable sections.

Many changes could be made in the constructions shown in order to carry my invention into practice, without departing from the spirit of my invention, and I consider part of my invention those apparently different embodiments of the same which may enter, fairly, into the scope of the appended claims.

I claim:

29 1. In a propeller, the combination of an axle, a plurality of flexible carriers attached thereto and extensible therefrom, plane elements carried by said carriers, and elastic means opposing the extension of said carriers.

2. In a propeller, the combination of an axle, a plurality of flexible carriers attached thereto and extensible therefrom, plane elements carried by said carriers, means caus-

30 ing variations in the angle of incidence of said planes as said carriers are extended or retracted, and elastic means opposing the extension of said carriers.

3. In a propeller, and in combination 35 with an axle, a plurality of outwardly extensible elements carried thereby, and elastic means opposing the outward motion of said elements, means under the control of the operator for establishing a rigid connection between said elements and said axle.

4. In a propeller having a variable pitch and a variable diameter, means causing said propeller to assume a negative pitch when reaching a predetermined diameter.

45 5. In a propeller, and in combination with an axle, and a plurality of extensible elements carried thereby, a fluid under pressure tending to oppose the extension of said elements.

50 6. In a propeller, the combination of an axle, a plurality of outwardly extensible elements carried thereby, elastic means tending to oppose the extension thereof, and means under the control of the operator 55 adapted to establish a rigid connection between said elements and said axle.

7. In a propeller, the combination of an axle, a plurality of flexible carriers attached thereto and extensible therefrom, plane elements carried by said carriers, elastic means 60 tending to oppose the extension of said carriers, and means under the control of the operator adapted to establish a rigid connection between said elements and said axle.

8. In a propeller, the combination of an axle, a plurality of flexible carriers attached thereto and extensible therefrom, plane elements carried by said carriers, elastic means tending to oppose the extension of said carriers, means causing variations in the angle 70 of incidence of said plane elements as said carriers are extended or retracted, and means under the control of the operator adapted to establish a rigid connection between said elements and said axle.

9. In a propeller, the combination of an axle, a plurality of flexible extensible elements attached thereto, winding means therefor, an elastic connection between said axle and said winding means tending to 80 operate said winding means in the winding direction, and means under the control of the operator adapted to establish a rigid connection between said winding means and said axle.

10. In a propeller, the combination of an axle, a plurality of flexible carriers attached thereto and extensible therefrom, winding means therefor, plane elements carried by said carriers, an elastic connection between 90 said axle and said winding means tending to operate said winding means in the winding direction, and means under the control of the operator adapted to establish a rigid connection between said winding means and 95 said axle.

11. In a propeller, the combination of an axle, a plurality of flexible carriers attached thereto and extensible therefrom, winding means therefor, plane elements carried by 100 said carriers, means causing variations in the angle of incidence of said plane elements as said carriers are extended or retracted, an elastic connection between said axle and said winding means tending to 105 operate said winding means in the winding direction, and means under the control of the operator adapted to establish a rigid connection between said winding means and said axle.

MARIO SCHIESARI.
